UNITED STATES PATENT OFFICE

134,550

DESIGN FOR A DRESS

Minna Wuerth, New York, N. Y.

Application November 17, 1942, Serial No. 108,807

Term of patent 3½ years

To all whom it may concern:

Be it known that I, Minna Wuerth, a citizen of the United States of America, residing in New York city, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

Fig. 3 is a fragmentary view of the front portion of the dress as illustrated in Fig. 1, with the belt portion in open position.

I claim:

The ornamental design for a dress, substantially as shown.

MINNA WUERTH.
